(57) **CLAIM**

The ornamental design for a loudspeaker front face, as shown and described.

DESCRIPTION

FIG. 1 is a top isometric view of a loudspeaker front face showing the new design;

FIG. 2 is a front elevational view thereof;

FIG. 3 is a rear elevational view thereof;

FIG. 4 is a side elevational view of one side thereof;

FIG. 5 is a side elevational view of the opposite side thereof;

FIG. 6 is a top plan view thereof; and,

FIG. 7 is a bottom plan view thereof.

The broken lines and unshaded areas form no part of the claimed design.

1 Claim, 7 Drawing Sheets

FIG. 2

FIG. 4

FIG. 6

FIG. 7
